UNITED STATES PATENT OFFICE.

EARNEST W. LADD, OF WASHINGTON, DISTRICT OF COLUMBIA, ASSIGNOR OF ONE-FOURTH TO HUNTER ARNOLD, ONE-EIGHTH TO WILLIAM H. ROHRER, ONE-EIGHTH TO HARRY L. WHEATLEY, AND ONE-EIGHTH TO B. M. McQUINN, ALL OF WASHINGTON, DISTRICT OF COLUMBIA, AND ONE-EIGHTH TO THOMAS J. FARRAR, OF VIRGINIA.

CUTTING-TOOL.

No. 865,918.

Specification of Letters Patent.

Patented Sept. 10, 1907.

Continuation of application Serial No. 321,416, filed June 12, 1906. This application filed January 28, 1907. Serial No. 354,535.

To all whom it may concern:

Be it known that I, EARNEST W. LADD, a citizen of the United States, residing at Washington, in District of Columbia, have invented certain new and useful 5 Improvements in Cutting-Tools; and I do hereby declare the following to be a full, clear, and exact description of the invention, such as will enable others skilled in the art to which it appertains to make and use the same.

10 My invention relates to cutting tools of the type employing a pair of pivotally connected and coöperating blades, has particular reference to scissors and shears, and is a continuation of my former application Serial No. 321,416. In the operation of tools of this type now 15 in general use, there is a well known tendency on the part of the blades to spread or spring apart thus seriously detracting from the proper coöperation of their cutting edges in effecting a clean, sharp cut, with a consequent detraction from the efficiency of the tool. Attempts 20 have been made to overcome this defect, notably by forming one or both of the blades, during the course of manufacture, with a protuberance or a pair of protuberances or heels, disposed in rear of the fulcrum of the blades, and adapted, during the cutting operation 25 to throw the forward, active portions thereof together in parallel lines. This mode of construction is, however, rendered objectionable by the fact that such protuberances or heels must necessarily be finished by hand, thus increasing the cost of manufacture, and, 30 moreover, such protuberances rapidly wear away, in practice, thus becoming ineffective for their intended purpose. Various other means have, heretofore been devised for the alleged purpose of overcoming the objection in question, but such devices have invariably 35 met with disfavor owing to their impracticability and high cost of production.

This invention has for its object to provide a simple, inexpensive and efficient means for imparting to the blades of scissors, shears and similar tools, a relative 40 twisting action during the operation of cutting, whereby the shearing edges are automatically caused to approach each other with gradually increasing force, and are thus maintained in proper coöperative relation throughout their entire length.

45 A further object of the present invention, is to effect a proper tensioning of the active portions of said blades, and to provide means whereby such tension will be automatically and gradually increased toward the outer ends or points thereof, as the cutting operation progresses; thus insuring proper coöperation of the blades 50 even to their extreme points for effecting a clean smooth cut.

A further object is to provide for positive and absolute adjustability of the aforesaid twisting and tensioning means, thus compensating for all wear of the moving contacting parts, and rendering such adjustable means readily detachable and replaceable. 55

A further object is to provide a tool of this type wherein the blades are self sharpening; a tool which cannot become deranged or get out of order owing to its 60 simplicity of construction; and one which is extremely economical of manufacture.

With these and other objects in view, this invention comprises the novel features of construction and combination of parts more fully hereinafter described. 65

In the accompanying drawings which form part of this application: Figure 1, represents in plan view a pair of closed shears embodying my invention. Fig. 2, is a fragmentary view showing a longitudinal section of the invention taken on the line 2-2 of Fig. 1. Fig. 3, is a detail transverse section taken on the line 3-3 of Fig. 1. Fig. 4, is a perspective view, partly in section, and partly broken away, showing the shears partially open. Fig. 5, is a detail plan view of the rear portion of one of the blades. 75

Reference being had to the drawings, it will be seen that the present tool comprises a pair of pivotally connected cutting blades 1 and 2 fulcrumed between their ends for relative movement upon the pivoting member or screw 3 and having at their rear ends handles or bows 80 4 of usual form, the forward active portions of the blades being provided with coöperating sharpened cutting edges 5. The foregoing parts of the tool are of usual well known construction and material, and, except in the particulars hereinafter explained, are adapted in 85 practice to perform their ordinary functions.

In accordance with my invention there is tapped centrally through the blade 1 at a point in rear of the pivoting screw 3 a combined twisting and tensioning member or screw 6, which latter is accordingly adjustable with relation to said blade, and is by preference of uniform size throughout its length, thus providing for, and permitting a comparatively extensive range of adjustment, or its ready removal if occasion should arise to withdraw and replace same. The inner end of said 90 twisting and tensioning member 6, as shown, bears upon the inner face of the adjacent portion of blade 2 and there presents an extended bearing surface toward said blade, with which, owing to its preferred location, it is at all times in contact; thus, insuring certainty of 95 action, and compensating for wear of the parts, as more fully hereinafter explained.

It will be noted that screw 6 riding over the inner face of blade 2, during the operation of cutting, causes a

relative tilting or twisting of the blades transversely to their direction of length; and, in addition a tilting of the blades longitudinally.

The operation is as follows: In practice, the handles 5 are grasped and the tool manipulated as usual, screw 6, adjustable with relation to blade 1, rides over the inner face of blade 2 causing a relative twisting of said blades transversely as indicated by the arrows *a* in Fig. 4, and as a consequence the cutting edges 5 of said 10 blades are brought into contact with gradually increasing force as the cutting operation progresses, and as said screw 6 approaches its resting place in the longitudinal center of blade 2. Simultaneously with said action, screw 6 in its passage over the inner face of 15 blade 2 as aforesaid, also slightly spreads the blades in rear of their pivotal point as indicated by the arrows *a* in Fig. 2, thus tensioning or throwing their forward active portions toward each other for maintaining them in proper coöperative relation. It will be apparent 20 also that the blades will thus be maintained under the proper and appropriate tension throughout their entire length as the cutting progresses, and further that the screw 6 may readily be adjusted to vary the tension according to the nature of the material acted upon.

25 In tools of the type under consideration, and particularly in shears of unusual length, there is a marked tendency of the blades to spring apart as the cutting progresses toward their outer ends or points, thus rendering the tools more or less defective in action. In 30 order to more effectually overcome this defect, I provide on the inner face of blade 2 at an appropriate point in rear of the pivot 3, a transversely inclined bearing surface 7 over which the inner end of screw 6 rides and which gradually increases in elevation from the outer 35 rear edge of blade 2 toward its longitudinal center. Thus it is apparent that as the blades are moved to closed position, screw 6 riding over said inclined surface 7 the more effectually produces the before mentioned transverse relative twisting of said blades and in 40 addition the longitudinal tensioning thereof; also that both of said results are not only automatic and simultaneous in their action, but are applied with gradually increasing force, and combine to insure proper coöperation of the blades throughout the entire length there- 45 of for effecting smooth, clean cutting of the material acted upon. It will be noted also that blades formed and assembled as hereinbefore described do not require the nicety of initial adjustment at hands of the manufacturer which is necessarily given tools of this type ordinarily, moreover the cost of manufacture is otherwise reduced as compared with the ordinary tools of like character and size. For example the grinding of the 50 blades is greatly facilitated by overcoming the necessity of hand finishing at the hilts or heels, since in carrying 55 out my invention it is unnecessary to produce upon the inner surface of blade 2 a clearly defined incline 7

as shown, but the full mechanical equivalent thereof may be formed with ease and facility by a slight twist of the blade at its hilt during the process of grinding.

Having thus described my invention what I claim 60 is:

1. In a cutting tool, the combination with a pair of pivotally connected blades, of separable means secured to one of said blades for imparting thereto a transversely twisting action with relation to the other of said blades, 65 substantially as described.

2. In a cutting tool, the combination with a pair of pivotally connected blades, of means adjustable with relation to one of said blades for imparting thereto a transversely twisting action with relation to the other of said 70 blades, substantially as described.

3. In a cutting tool, the combination with a pair of pivotally connected blades, of means adjustable with relation to one of said blades for imparting thereto a transversely twisting and tensioning action with relation to 75 the other of said blades, substantially as described.

4. In a cutting tool, the combination with a pair of pivotally connected blades, of means adjustable with relation to one of said blades located in rear of the pivotal point for imparting a transversely twisting action to said 80 blades, substantially as described.

5. In a cutting tool, the combination with a pair of pivotally connected blades, of means carried by one of said blades and adjustable with relation thereto for imparting a transversely twisting action to said blades, 85 substantially as described.

6. In a cutting tool, the combination with a pair of pivotally connected blades, of an adjustable tensioning member interposed between said blades adapted to impart a transversely twisting action thereto, substantially as de- 90 scribed.

7. In a cutting tool, the combination with a pair of pivotally connected blades, of an adjustable tensioning member threaded through one of said blades and bearing upon the other of said blades for imparting a transversely 95 twisting action thereto, substantially as described.

8. In a cutting tool, the combination with a pair of pivotally connected blades, of an incline upon one of said blades, and an adjustable tensioning member carried by the other of said blades adapted to traverse the incline 100 aforesaid for imparting to the blades a transversely twisting action, substantially as described.

9. In a cutting tool, the combination with a pair of pivotally connected blades, of an incline upon one of said blades in rear of its pivotal point, and an adjustable tensioning member carried by the other of said blades adapted to traverse the incline aforesaid for imparting to the 105 blades a transversely twisting action, substantially as described.

10. In a tool of the type described, a pair of crossed pivoted blades having sharpened inner edges, one of said blades being provided on its inner face and in rear of its fulcrum with a transversely disposed inclined bearing face, and a rigid unyielding tensioning member carried by the other blade to ride on said bearing face for throwing the 115 outer ends of the blades together, said tensioning member being adjustable to compensate for wear.

In testimony whereof I affix my signature, in presence of two subscribing witnesses.

EARNEST W. LADD.
